US00D952946S

(12) **United States Design Patent** (10) Patent No.: **US D952,946 S**
(45) Date of Patent: **** May 24, 2022**

(54) **HAIR REMOVAL DEVICE**(71) Applicant: **Church & Dwight Co., Inc.**, Princeton, NJ (US)(72) Inventors: **Anand Khubani**, Morristown, NJ (US); **Eric Langberg**, Milford, PA (US); **Aaron Szymanski**, Thomaston, CT (US); **LoriAnn Lombardo**, East Hanover, NJ (US)(73) Assignee: **Church & Dwight Co., Inc.**, Princeton, NJ (US)(***) Term: **15 Years**(21) Appl. No.: **29/719,309**(22) Filed: **Jan. 2, 2020****Related U.S. Application Data**

(63) Continuation-in-part of application No. 29/651,665, filed on Dec. 6, 2018, now Pat. No. Des. 873,490, which is a continuation-in-part of application No. 29/620,951, filed on Sep. 1, 2017, now Pat. No. Des. 849,325.

(51) LOC (13) Cl. .... **28-03**(52) U.S. Cl. **D28/51**
USPC ....(58) **Field of Classification Search**USPC **D28/49-54**
CPC B26B 19/00-08; B26B 19/10-12; B26B 19/20-24; B26B 19/26-265; B26B 19/38-3826; B26B 19/3873-3893; B26B 19/42

(57) CLAIM

The ornamental design for a hair removal device, as shown and described.

DESCRIPTION

FIG. 1 is a front perspective view of a first embodiment of a hair removal device of the present invention showing our new design;

FIG. 2 is a front elevation view thereof;

FIG. 3 is a back elevation view thereof;

FIG. 4 is a side elevation view thereof;

FIG. 5 is a top plan view thereof;

FIG. 6 is a bottom plan view thereof;

FIG. 7 is a front perspective view of a second embodiment of a hair removal device of the present invention showing our new design;

FIG. 8 is a front elevation view thereof;

FIG. 9 is a back elevation view thereof;

FIG. 10 is a side elevation view thereof;

FIG. 11 is a top plan view thereof;

FIG. 12 is a bottom plan view thereof;

FIG. 13 is a front perspective view of a third embodiment of a hair removal device of the present invention showing our new design;

FIG. 14 is a front elevation view thereof;

FIG. 15 is a back elevation view thereof;

FIG. 16 is a side elevation view thereof;

FIG. 17 is a top plan view thereof; and,

FIG. 18 is a bottom plan view thereof.

The broken lines illustrate portions of the hair removal device that form no part of the claimed design.
